**PRODUCTION OF PRIMARY ALKYLAROMATICS
FROM SECONDARY AND TERTIARY ALKY-
AROMATICS**

John H. Raley, Walnut Creek, and Lynn H. Slaugh, Pleasant Hill, Calif., assignors to Shell Oil Company, New York, N.Y., a corporation of Delaware
No Drawing. Filed June 25, 1959, Ser. No. 822,729
7 Claims. (Cl. 260—668)

This invention relates to the selective catalytic isomerization of substituted aromatics having at least one side chain of alkyl character attached through a secondary or tertiary alkyl carbon atom to produce an isomer having the side chain attached through a primary alkyl carbon atom.

While certain of the lower alkylaromatic hydrocarbons such as toluene and xylene may be recovered from cracked petroleum fractions, coal tar products, and the like, those containing side chains having 3 or more carbon atoms are generally too costly to separate and are normally prepared by alkylating a suitable aromatic hydrocarbon, e.g., benzene, xylene, naphthalene, or the like, with an appropriate olefinic material. In such alkylation the point of attachment of the side group is through a tertiary carbon atom or through a secondary carbon atom, but not through a primary carbon atom. Thus, alkylation with propylene yields the isopropyl derivatives (secondary carbon attachment), butene-1 and butene-2 give the secondary butyl derivatives, and isobutylene yields the tertiary butyl derivatives. The corresponding normal derivatives, i.e. attached through a primary carbon atom, are not formed.

While the substituted aromatic hydrocarbons having the side group attached through a secondary or tertiary carbon atom are therefore readily prepared and available for commercial use, those having groups of 3 or more carbon atoms attached through a primary carbon atom require a much more involved synthesis. While these latter may be purchased as fine chemicals for research at a cost of several dollars per pound they have not been, up to the present, available in quantities and at a cost conducive to commercial use.

It is known that alkylaromatics can be isomerized with various Lewis acid type catalysts such, for example, as AlCl_3 , FeCl_3 , P_2O_5 , HF-BF_3 , and the like. This isomerization generally takes place at relatively low temperatures. However, even at relatively low temperatures the isomerization is accompanied by disproportionation and usually by appreciable cracking and degradation to tars and the like.

The primary isomerization with acid catalysts and when at least two alkyl groups are present involves a shift of the alkyl side chains towards equilibrium between the position isomers, i.e. the ortho, meta and para isomers. (See Norris, J. F. and Vaala, G. T. *Ind. Eng. Chem.*, 61, 2131-2134 (1939).)

Disproportionation also takes place to a considerable extent and in two ways. Firstly, there is considerable shift of groups from one aromatic ring to another or, in effect, dealkylation of some molecules with further alkylation of others. Thus, for example, the isomerization of xylenes leads to the formation of benzene, toluene,

2

and higher boiling polymethylated benzenes in addition to the position isomers. (See Baddeley, G. and Kenner, J., *J. Chem. Soc.*, 303 (1935).)

The other or second type of disproportionation reaction occurs between alkyl groups and is exemplified by the conversion of xylene to ethylbenzene. This type of disproportionation becomes of importance when using certain types of isomerization catalysts. (See Holzman, G. and Good, U.S. 2,656,397.)

10 In a few cases where a normal C_3 side chain is present in the initial material subjected to an isomerization treatment with AlCl_3 it has been reported that the side chain may simultaneously isomerize to an "iso" side chain while changing position on the aromatic nucleus. Thus, 1-n-
15 propyl-2,4-dimethylbenzene has been reported to isomerize to 1,3-dimethyl-5-isopropylbenzene. (See Nightengale, D. and Carton Jr., B., *J. Am. Chem. Soc.*, 62, 280-283 (1940).) This is, however, quite different than the isomerization sought and obtained by the present
20 invention. Moreover, there is some question as to whether or not such isomerization actually takes place. (See Condon, F. E. in *Catalysis VI*, Emmett, C. H., p. 107 New York, Reinhold Publishing Company (1958).)

Thus, side chains attached through a primary carbon atom migrate on the aromatic nucleus but isomerization from a secondary side chain to a normal side chain or of a tertiary side chain to an "iso" side chain clearly does not take place. (See McCaulay, D. A., and Lien, A. D., *J. Am. Chem. Soc.*, 75, 2411 (1953).)

30 The experimentally observed isomerizations of alkylaromatics mentioned above have quite conclusively been shown to take place by a carbonium ion mechanism. On the basis of the carbonium ion theory, and in keeping with the experimentally determined results, we would not
35 expect to be able to convert an alkylaromatic having a secondary or tertiary side chain into an isomer having the corresponding normal or "iso" side chain by a carbonium mechanism.

If an alkylaromatic is treated under drastic conditions
40 without any catalyst, i.e. thermally at cracking or incipient cracking temperatures, a small amount of isomerization from a secondary alkyl group to a primary alkyl group takes place. (See Ipatieff, V. N., Pines, H., and Kvetinskas, B., U.S. Patent No. 2,671,120.) However, this requires the use of very high pressures. Also
45 the reaction is accompanied by cracking and other side reactions. Thus, in the case of isopropylbenzene (the most stable of the alkyl aromatics under consideration) at 3000 p.s.i.g. and 475° C. no reaction takes place; at 12,000 p.s.i.g. and 479° C. about 22% of the isopropylbenzene is reacted giving 12.7% of normal-propylbenzene at 9.3% of cracked products; at 12,000 p.s.i.g. and 501° C. 44.5% of the isopropylbenzene is reacted giving 14.8% normal-propylbenzene and 29.7% of cracked products.

55 We have now discovered that by employing different and selected conditions whereby a catalytic free radical mechanism controls it is indeed possible for the first time to catalytically isomerize aromatic hydrocarbons having one or more groups attached through a secondary or tertiary alkyl carbon atom to the corresponding isomer having the group attached through a primary carbon atom. Thus, it is now possible to isomerize tertiary groups to "iso" groups and secondary groups to normal groups. Moreover it is found that the isomerization can

be made quite selective, i.e. to take place without migration of the groups and with little cracking, dehydrogenation, polymerization, or other side reactions. Good yields may therefore be obtained and the process for the first time allows the desirable primary isomers to be produced from the secondary and tertiary isomers at a cost which is not prohibitive for commercial application.

It may be noted that it has been indicated that the neophyl radical is capable of rearrangement to give some of the corresponding isobutyl grouping. (See Kharasch, M. S., and Urry, W. H., J. Am. Chem. Soc., 66, 1438 (1944) and Winstein, S., and Seubold, F., J. Am. Chem. Soc., 69, 2916 (1947).) This work, however, did not involve isomerization of an alkylaromatic hydrocarbon and it involved a stoichiometric rather than a catalytic method. In the first case, 1-chloro-2-methyl-2-phenylpropane reacted with a stoichiometric quantity of a Grignard reagent in the presence of cobaltous chloride catalyst. In the second case a stoichiometric amount of 3,3-dimethyl-3-phenylpropionaldehyde was decomposed with a peroxide. The mechanism postulated to explain the mixture of products obtained involved rearrangement of the neophyl radical as stated above.

The process of the invention is applicable for the isomerization of mononuclear and polynuclear aromatics, as hereinafter defined, having at least one hydrogen atom substituted by a side group which is essentially a hydrocarbon group containing at least three carbon atoms of which at least two and preferably not more than five are alkyl carbon atoms, said group being attached to the aromatic nucleus through a secondary or tertiary carbon atom. This definition is intended to include true alkyl groups having three to five alkyl carbon atoms, e.g. the propyl group, and also alkyl groups having an aromatic substituent attached. Thus, the lowest member of the first type is cumene and the lowest member of the second type is 1,1-diphenyl ethane.

When the attached group is connected through a secondary alkyl carbon atom the isomer produced has the group attached through a primary carbon atom. When the attached group is connected through a tertiary carbon atom the isomer is also attached through a primary carbon atom but the group is normally of the "iso" configuration. An exception is the case where the alkyl group is a tertiary amyl group in which case the isomerization may be such that the attachment is shifted from the tertiary carbon atom to the secondary carbon atom as well as to one of the primary carbon atoms.

The side group is preferably free of ethylenic and acetylenic unsaturation because compounds containing side groups having such unsaturation are generally quite prone to polymerization or undergo other side reactions under the reaction conditions. Compounds having any individual side groups having more than five connected alkyl carbon atoms are generally not suitable starting materials since the large number of non-profitable points of attack by free radicals favor side reactions to an excessive extent. Thus, while aromatics having a highly branched alkyl side chain up to around eight carbon atoms might be profitably isomerized (depending upon economics) it is generally recommended to retain the maximum size of any individual alkyl group to not more than six and preferably not more than five carbon atoms.

There may be only one side chain attached to the aromatic nucleus as for example, isopropyl benzene which is the lowest member, or on the other extreme, each of the hydrogens of a polycyclic aromatic may be substituted by a side group, as above defined, up to the limit imposed by steric hindrance.

The groups attached to the aromatic nucleus may be the same or different, provided that the largest alkyl group does not have more than about 5 carbon atoms. Thus, the alkylaromatic hydrocarbon may contain any number of possible additional methyl, ethyl, phenylmethyl, phenylethyl, etc. side groups.

The isomerization is effected at temperatures between about 350 and 525° C. and, in general, temperatures between about 400 and 475° C. are preferable with most of the applicable catalysts. At temperatures below about 350° C. the isomerization is generally too slow to be practicable in commercial operation and at temperatures above about 525° C. the alkylaromatics are cracked and dehydrogenated to such an extent that reasonable yields of the desired isomer are not obtained.

10 The isomerization may be effected with the alkylaromatic in the vapor phase, but good results may also be obtained when the alkylaromatic is maintained largely, if not completely, in the liquid phase. Pressures from atmospheric to 2000 p.s.i.g. have been successfully employed. Suggested pressures are from about 50 to about 1000 p.s.i.g.

15 The contact time to be used to obtain selective isomerization depends upon the conditions and may range from about 1/2 minute to about 5 hours. The contact time in this case is the so-called "nominal contact time" computed from the molar input rate at the reaction temperature and pressure and considering the vapors to conform to the laws for perfect gases. The optimum contact time is shorter the higher the temperature and vice versa and depends somewhat on the catalyst used, the amount of catalyst used, and the particular alkylbenzene being isomerized. When operating at the lowest possible temperature with the alkylaromatic in the liquid phase contact times up to about 5 hours may be used or required. An important point to be observed is that the contact time should not be appreciably longer (with the feed, catalyst, and temperature) than that necessary to achieve a reasonable approach to the equilibrium concentration ratio of the feed isomer to the product isomer.

20 It is recommended to limit the contact time in any case such that the conversion to the desired isomer does not give a concentration more than 95% of that corresponding to the equilibrium concentration under the reaction conditions since it has been found that any longer contact time leads only to appreciable side reactions and loss of the desired isomer.

25 Diluents which are substantially inert under the processing conditions may be included with the feed if this is desirable, e.g., to avoid an unnecessary step in separating them prior to isomerization. For instance, an aromatic hydrocarbon or mixture of aromatic hydrocarbons may be alkylated with an olefinic gaseous fraction of C₁-C₄ hydrocarbons obtained in the cracking of a petroleum oil in which case a mixture of ethyl, isopropyl, and tertiary-butyl alkylated aromatics is obtained; some of these are susceptible to isomerization according to the invention and others are not. Such complicated mixtures may be isomerized but their use is not recommended. As another example, a highly aromatic fraction obtained 30 by the catalytic reforming of a naphthenic petroleum fraction and containing various aromatics as well as paraffins and unconverted naphthenes may be alkylated with propylene or butylene and the product then isomerized. This also, although possible, generally involves complicated separation problems and is not recommended where separation of a single isomer is the objective. Hydrogen, carbon dioxide, carbon monoxide, nitrogen, methane and similar inert gases may be present as diluents in most cases although their presence in appreciable amounts offers no advantage of consequence. Some materials such as water (steam), alcohols, and other oxygenated materials exert no harmful effects in small concentrations but may be harmful in concentrations above a few percent. Oxygen per se is not harmful in small amounts and in fact in many cases a small percentage of elemental oxygen is beneficial.

35 As indicated above, the process of the invention is dependent upon selecting conditions conducive to a free radical chain reaction mechanism. This requires the use,

not only of the prescribed operating conditions but also, of a catalytic amount of a suitable catalyst capable of initiating and maintaining the free radical reaction under the prevailing conditions. In principle, any compound is applicable which under the operating conditions is capable of producing in catalytic amounts free radicals that reversibly abstract hydrogen atoms. Those skilled in the art of free radical reactions will recognize this class of catalysts. (See, for example, Steacie, E. W. K., "Atomic and Free Radical Reactions," Reinhold Publishing Corporation, New York (1954), and especially vol. I, pages 253-273.)

Excellent catalysts are the elements bromine, iodine, sulfur, selenium and tellurium as such and in the form of their hydrides and semi-labile organic compounds, e.g. the analogs of hydrocarbons, alcohols, ethers, ketones, aldehydes, acids, esters, amines, amides, nitriles and the like. Of these materials those containing bromine are generally better than most of the others.

While the above-mentioned materials and others are operable in at least some cases it is not to be inferred that they are equivalent. The corresponding materials in which chlorine is substituted for one of the above can also be used in many cases but are generally inferior. On the other hand, whereas bromine, iodine, hydrogen bromide and hydrogen iodide are excellent catalysts, chlorine reacts immediately with the hydrocarbon to form hydrogen chloride which is very stable under most reaction conditions and is generally a poor catalyst. Similarly, whereas sulfur and chloroacetone are good catalysts, the bond to the sulfur or chlorine in such compounds as thiophene and chlorobenzene is so strong that few free radicals are produced under the reaction conditions and hence the isomerization is catalyzed only to a small extent. In keeping with the above rules, benzyl bromide is a better catalyst than iodine or isopropyl iodide; mercaptans and disulfides are for the same reasons less effective than the iodides and bromides under comparable conditions.

In general, when using the sulfur, selenium or tellurium-containing catalysts, the concentration based on the catalytic element should be somewhat higher on a mole basis than when using catalysts containing bromide or iodine. However, if too large a concentration of sulfur containing catalyst, e.g. mercaptan and sulfides, is used, unsaturated products such as alpha and beta-methylstyrene become important side reaction products. This is particularly important when operating at low conversion levels. On the other hand, in the isomerization of cumene with isopropyl iodide as the catalyst, an increase of the iodine equivalent from 1 mole percent to 5 mole percent affords an increase in the conversion from about 40% to about 60% without materially affecting the selectivity which was about 70%. As thus indicated, it is preferable in seeking higher conversion in any particular case to vary the concentration of the catalyst in preference to unduly increasing the contact time, since increasing the contact time, although increasing the conversion, leads generally to increased side reaction products and lower selectivity without a commensurate increase in the desired isomer.

The function of the above mentioned catalysts is improved if a small amount, e.g. 0.1 to 3 mole percent of oxygen (O_2) is introduced along with the catalyst.

Examples of some catalysts that have been successfully used are bromine, organic bromides exemplified by benzyl bromide; iodine, organic iodides exemplified by 2-iodopropane and iodobenzene; organic sulfur compounds exemplified by thiophenol, diphenyl disulfide, ethyl mercaptan; organic chlorides exemplified by 2-chloropropane; sulfur, and hydrogen sulfide.

Elemental chlorine is operative although it generally

reacts immediately, especially if light is present. It is, therefore, the resulting chloride which actually acts as the catalyst. This is probably likewise the case at least to some extent with bromine, iodine and sulfur.

5 Merely by way of comparison some materials that were tested and found to be inoperative are a potassium promoted chromia-alumina catalyst with and without hydrogen present, Columbia activated carbon, aluminum chloride, various nickel sulfide catalysts having various atomic ratios of nickel to sulfur.

10 The operable materials act as catalysts and not as reactants and are used only in catalytic amounts, e.g. 0.1 to 3 mole percent. In general, only a fraction of 1 mole percent of the catalyst, based on the feed, is required and in general it is preferred to employ concentrations not in excess of about 3 mole percent; however concentrations as high as 10 mole percent have been employed successfully in some cases. It will be noted that some of 15 the applicable catalysts, and especially those in elemental form, are capable of reacting stoichiometrically and those, in particular, should be used in only small concentrations, e.g., less than 3 mole percent, to preserve the selective isomerization desired. In any case as a criterion 20 of catalytic operation the moles of isomer formed should exceed by several fold the moles of catalyst used.

25 The catalyst is preferably mixed with the feed to be isomerized prior to charging to the reaction zone, but it may, if desired, be charged separately to the reaction zone either at a single point or at multiple points. No particular advantage is seen, however, in the latter type of operation.

30 The reaction zone wherein the alkyl aromatic feed and catalyst are contacted may be an empty reaction chamber with means for maintaining the desired temperature, pressure, and flow rate, or it may be packed with a substantially inert foraminous solid material to improve the transfer of heat. Obviously, from what has been shown 35 above, no material inducing carbonium ion isomerization to any appreciable extent should be present in the reaction zone since the presence of such material detracts materially from the efficiency and selectivity of the isomerization process. In general, the preferred reaction zone consists of one or more cylindrical and vertically disposed chambers either empty of solids or containing a relatively inert fixed bed or fluidized bed of solid material through which the material to be isomerized is passed, along with the catalyst, in a continuous manner. Since the isomerization is for all practical purposes thermally neutral there is little to be gained by the use of such solid material. Batchwise processing in a bomb type reactor is also possible but less desirable for commercial 40 operation.

45 The materials of which the reactor is constructed or lined depends primarily upon the choice of catalyst and the pressure. In many cases mild steel may be used; in other cases vessels constructed of or lined with corrosion 50 resistant material may be advisable or necessary.

55 The isomerized alkylaromatic containing the alkyl side chain attached through a primary carbon atom may in general be recovered from the reactor effluent in a simple manner. Generally, the effluent may be washed with water or an alkali to destroy or render harmless any corrosive material, and then fractionally distilled to recover the desired isomer. In some exceptional cases separation by more elaborate treatments, e.g., molecular sieve separation or solvent treatments, may be more economical. The unconverted material may be recycled to the reaction zone with fresh catalyst, or in some cases the bottoms from the distillation contain sufficient of the catalyst and may be also recycled in whole or in part.

The isomerized products obtainable by the method of the invention are chiefly of value as intermediates in the production of industrial chemicals. By way of example, the invention allows epoxidized beta-methylstyrene, allylbenzene, diallylbenzene, and phenylbutadiene and many other desirable intermediates to be produced in a better and more practicable manner. The epoxidized beta-methylstyrene is equally suitable for applications where epoxidized styrene or alpha-methylstyrene have been used, e.g., as a cross linking agent in resinous polymers. One suggested synthesis of this material follows: Benzene is alkylated with propylene in the known manner. The resulting isopropylbenzene is separated from the product and isomerized to normal-propylbenzene in accordance with the present process. The normal-propylbenzene is dehydrogenated by known methods to produce beta-methylstyrene which is then epoxidized in the manner that styrene is epoxidized. If para-diisopropylbenzene is recovered from the alkylation product and handled in the same manner the resulting epoxy product is an excellent resin monomer.

Allylbenzene may be prepared in a similar manner except that instead of epoxidizing the beta-methylstyrene it is isomerized in a known manner by reacting with an alkyl boron compound followed by decomposition whereupon the allylbenzene is produced.

Phenylbutadiene may be produced by alkylating benzene with butene-1 or butene-2 and isomerizing the resulting secondary-butyIbenzene as described to produce the normal-butyIbenzene. The normal-butyI side chain may then be dehydrogenated to an olefinic side chain by reacting with the stoichiometric quantity of iodine and the resulting unsaturated compound can then be further dehydrogenated to the diene using the methods used for the dehydrogenation of butene-2 to butadiene.

The process of the invention will be illustrated by a number of examples which will also indicate the effects of the conditions upon the conversion and selectivity.

EXAMPLE I

A series of isomerizations of isopropylbenzene was made using 1 mole percent iodine as the catalyst. The isopropylbenzene and iodine were charged to a pressure

Table I

	Temp., ° C.	Time, min.	Conversion, Percent	Selectivity, Percent	n-propyl benzene moles/100 moles feed
5	450	11.0	10.2	98.4	10.1
	500	8.7	23.7	84.4	20.1
	525	7.9	59.2	36.1	21.4

It is evident that for this catalyst in this amount with this feed a temperature of 450° C. gives a fair conversion with essentially perfect selectivity. Increasing the temperature more than doubles the conversion while retaining excellent selectivity. However, increasing the temperature to 525° C. results in a substantial loss in the selectivity.

EXAMPLE II

A series of isomerizations of cumene was made as in Example I except at a constant temperature of 500° C. In this series 2 mole percent catalyst was used at 500 p.s.i.g. The results are shown in Table II.

Table II

	Catalyst	Time, min.	Conversion, Percent	Selectivity, Percent	n-propylbenzene moles/100 moles feed
25	Benzyl bromide	10.5	41.3	81	33.5
	Isopropyl iodide	ca. 11	38.9	72.6	28.2
	Benzyl bromide	6.0	36.8	84.6	31.1
	Isopropyl chloride	10.4	4.7	-----	2.1
30	None	7.8	5.3	-----	1.0

When the concentration of isopropyl iodide was increased to 10 mole percent, other conditions remaining the same, the conversion increased to 60.5% but the selectivity declined to 66.4%.

When with 2 mole percent isopropyl iodide the pressure was increased to 1000 p.s.i.g. no change in the yields resulted.

EXAMPLE III

The use of some sulfur compounds as catalyst is illustrated by the results shown in Table III. The pressure was 500 p.s.i.g.

Table III

Catalyst	Mole, Percent	Temp., ° C.	Time, min.	Conv., Percent	Select., Percent	n-propylbenzene, moles/100 moles feed
(C ₆ H ₅ S) ₂	1	500	5.0	1.8	-----	1.2
(C ₆ H ₅ S) ₂	5.0	500	5.0	20.2	64.0	12.9
(C ₆ H ₅ S) ₂	1.0	525	10.0	18.7	33.7	6.3
C ₆ H ₅ SH	10.0	500	11.1	19.3	63.1	12.2
+	2.5	500	10.3	33.1	70.5	23.3
O ₂	5.0	500	10.0	36.6	49.6	18.1
(C ₆ H ₅ S) ₂	5.0	525	10.0	15.2	68.4	10.4
C ₂ H ₅ SH	10.0	500	10.0	-----	-----	-----
+	1.3	525	10.0	-----	-----	-----
O ₂	10.0	500	10.0	-----	-----	-----

bomb from which they were continuously fed at a desired rate through a reaction tube under a pressure of 500 p.s.i.g. The temperatures, contact times, conversions and selectivities are shown in the following Table I.

60 The results of a number of isomerizations of tertiary-butyIbenzene to isobutyIbenzene are given in Table IV. All of the runs listed were effected at 500 p.s.i.g.

Table IV

Catalyst	Mole, Percent	Temp., ° C.	Time, min.	Conv., Percent	Select., Percent	IsobutyIbenzene, moles/100 moles feed
Isopropyl iodide	2.0	450	11.1	19.3	92.9	17.7
Do	2.0	450	10.2	16.1	95.1	15.3
Do	2.0	500	11.0	52.6	51.8	28.8
C ₆ H ₅ CH ₂ Br	2.0	500	5.1	55.4	61.0	34.0
C ₆ H ₅ CH ₂ Br	2.0	525	10.0	74.8	21.7	16.2
C ₆ H ₅ CH ₂ Br	2.0	450	20.0	39.1	93.6	36.6
C ₆ H ₅ CH ₂ Br	10.0	450	22.0	63.6	84.1	53.5

All of the above runs shown in Examples I through IV were made by continuously passing the hydrocarbon and catalyst through the unpacked reaction zone, as mentioned. The runs shown in the next following Table V were carried out batchwise in an autoclave.

Table V

Feed	Catalyst	Mole, percent	Temp., °C.	P.s.i.g.	Time, hrs.	Conv., percent	Select., percent	isomerized product, moles/100 moles feed
Cumene.....	I ₂	1.0	400	500	3.0	45.0	75.5	34.0
Do.....	I ₂	1.0	450	750	1.0	71.9	60.7	43.7

Do.....	Amorph. S.	4.0	450	800	1.0	36.3	75.0	27.2
Do.....	H ₂ S	4.0	450	800	1.0	54.5	62.4	34.1

Regarding the results shown in Table V it will be noted that for comparison some inoperative materials and conditions have been included. Regarding the temperatures and times noted it should be pointed out that the time for heating and cooling the autoclave varied somewhat. The pressures noted are the maximum pressures attained.

For exploratory work, tests were carried out in sealed glass tubes. The success of such tests proves that the presence of metal surface is not necessary for the catalysis of the isomerization reaction. For example, cumene was sealed with 1 mole percent (C₆H₅S)₂ and heated at 500° C. for one hour. This resulted in 61.5% conversion with 54.3% selectivity giving 33.4% of the desired n-propylbenzene.

It should be pointed out that in contrast to the isomerization of alkylaromatics with Lewis acid catalysts very little, if any (ca 0.2%) disproportionation and ring migration occurred in any of the above examples. For example, in the isomerization of p-cymene 1-methyl-4-n-propylbenzene was produced but no m-cymene or 1-methyl-3-n-propylbenzene could be found by infrared analysis. Also the amount of coke formation was always very small.

In the above we have described the isomerization of alkylaromatics having the alkyl group attached to the aromatic through a secondary or tertiary carbon atom, i.e. a carbon atom having not more than one hydrogen atom and no double bond, and the subjoined claims are limited to this isomerization. The question therefore naturally arises as to the reverse isomerization. The reverse isomerization does take place but only to a very limited extent due to the relative stabilities of the isomers for which reason the control of the contact time is important as specified above. Also of importance is the fact that there is no economic incentive to effect the reverse isomerization of a valuable material to one of less value.

We claim as our invention:

1. Process for the production of aromatic hydrocarbons having at least one side group of at least three carbon atoms connected through a primary carbon atom in an alkyl group having not more than five carbon atoms which comprises adding a catalytic amount of a free radical-forming catalyst containing an element selected from the group consisting of Cl, Br, I, S, and combinations thereof, in a form selected from the group consisting of the free elements, their hydrides, and semi-labile organic compounds thereof, to an aromatic hydrocarbon having at least one side group of at least three carbon atoms connected through a non-primary alkyl carbon atom in an alkyl group having not more than five carbon atoms, maintaining the mixture at a temperature between about

350° C. and about 525° C. for a time between about 1/2 minute and 5 hours sufficient to effect substantial catalytic isomerization but insufficient for the concentration of the formed isomer containing the alkyl group attached through a primary alkyl carbon atom to exceed 95% of

the equilibrium concentration thereof at the reaction temperature, and separating as the major reaction product the said isomer having the alkyl group attached through a primary alkyl carbon atom.

2. Process for the production of aromatic hydrocarbons having at least one side group of at least three carbon atoms connected through a primary carbon atom in an alkyl group having not more than five carbon atoms which comprises adding a catalytic amount of a free radical-forming catalyst containing I in a form selected from the group consisting of the free element, its hydrides, and semi-labile organic compounds thereof, to an aromatic hydrocarbon having at least one side group of at least three carbon atoms connected through a non-primary alkyl carbon atom in an alkyl group having not more than five carbon atoms, and maintaining the mixture at a temperature between about 350° C. and about 525° C. for a time between about 1/2 minute and 5 hours sufficient to effect substantial isomerization but insufficient for the concentration of the formed isomer containing the alkyl group attached through a primary alkyl carbon atom to exceed 95% of the equilibrium concentration thereof at the reaction temperature, and separating as the major reaction product the said isomer having the alkyl group attached through a primary alkyl carbon atom.

3. Process for the production of aromatic hydrocarbons having at least one side group of at least three carbon atoms connected through a primary carbon atom in an alkyl group having not more than five carbon atoms which comprises adding a catalytic amount of a free radical-forming catalyst containing bromine in a form selected from the group consisting of the free element, its hydrides, and semi-labile organic compounds thereof, to an aromatic hydrocarbon having at least one side group of at least three carbon atoms connected through a non-primary alkyl carbon atom in an alkyl group having not more than five carbon atoms, and maintaining the mixture at a temperature between about 350° C. and about 525° C. for a time between about 1/2 minute and 5 hours sufficient to effect substantial isomerization but insufficient for the concentration of the formed isomer containing the alkyl group attached through a primary alkyl carbon atom to exceed 95% of the equilibrium concentration thereof at the reaction temperature, and separating as the major reaction product the said isomer having the alkyl group attached through a primary alkyl carbon atom.

4. Process for the production of a normal-propyl aromatic hydrocarbon which comprises adding a catalytic amount of a free radical-forming catalyst containing an element selected from the group consisting of Cl, Br, I, S, and combinations thereof in a form selected from the

group consisting of the free elements, their hydrides, and semi-labile organic compounds thereof, to an isopropyl aromatic hydrocarbon containing no alkyl group having more than 5 carbon atoms, maintaining the mixture at a temperature between about 350° C. and 525° C. for a time between about 1/2 minute and 5 hours sufficient to effect substantial catalytic isomerization but insufficient for the concentration of the normal-propyl isomer to exceed 95% of the equilibrium concentration thereof at the reaction temperature, and separating as the major reaction product said normal-propyl aromatic hydrocarbon.

5. Process for the production of an isobutyl aromatic hydrocarbon which comprises adding a catalytic amount of a free radical-forming catalyst containing an element selected from the group consisting of Cl, Br, I, S, and combinations thereof in a form selected from the group consisting of the free elements their hydrides, and semi-labile organic compounds thereof, to tert-butyl aromatic hydrocarbon containing no alkyl group having more than 5 carbon atoms, maintaining the mixture at a temperature between about 350° C. and 525° C. for a time between about 1/2 minute and 5 hours sufficient to effect substantial catalytic isomerization but insufficient for the concentration of the isobutyl isomer to exceed 95% of the equilibrium concentration thereof at the reaction temperature, and separating as the major reaction product said isobutyl aromatic hydrocarbon.

6. Process for the production of 1-methyl-4-normal-propyl-benzene which comprises adding a catalytic amount of a free radical-forming catalyst containing an element selected from the group consisting of Cl, Br, I, S,

and combinations thereof in a form selected from the group consisting of the free elements, their hydrides, and semi-labile organic compounds thereof, to 1-methyl-4-isopropyl-benzene, maintaining the mixture at a temperature between about 350° C. and 525° C. for a time between about 1/2 minute and 5 hours sufficient to effect substantial catalytic isomerization but insufficient for the concentration of the produced isomer to exceed 95% of the equilibrium concentration thereof at the reaction temperature, and separating as the major reaction product said 1-methyl-4-isopropylbenzene.

7. Process for the production of 1,2-diphenylethane which comprises adding a catalytic amount of a free radical-forming catalyst containing an element selected from the group consisting of Cl, Br, I, S, and combinations thereof in a form selected from the group consisting of the free elements, their hydrides, and semi-labile organic compounds thereof, to 1,1-diphenylethane maintaining the mixture at a temperature between about 350° C. and 525° C. for a time between about 1/2 minute and 5 hours sufficient to effect substantial catalytic isomerization but insufficient for the concentration of the 1,2-isomer to exceed 95% of the equilibrium concentration thereof at the reaction temperature, and separating as the major reaction product said 1,2-diphenylethane.
